CHARM BRACELET OR THE LIKE

Adolph Katz, Providence, R. I., assignor to Coro, Inc.,
New York, N. Y., a corporation of New York

Application June 16, 1955, Serial No. 36,547

Term of patent 7 years

(Cl. D45—16)

Fig. 1

Fig. 3

Fig. 1 is a plan view of a charm bracelet or the like showing my new design.

Fig. 2 is an edge view of the charm portion.

Fig. 3 is a bottom plan view.

The dominant feature of my design resides in the portions shown in solid lines.

I claim:

The ornamental design for a charm bracelet or the like, substantially as shown and described.
